UNITED STATES PATENT OFFICE.

JOSEPH JAKUBIEC, OF UHRICHSVILLE, OHIO.

COMBINED SAFETY RAZOR AND HAIR CLIPPER.

Application filed January 20, 1922. Serial No. 530,531.

To all whom it may concern:

Be it known that I, JOSEPH JAKUBIEC, a citizen of Poland, residing at Uhrichsville, in the county of Tuscarawas and State of 5 Ohio, have invented certain new and useful Improvements in Combined Safety Razors and Hair Clippers, of which the following is a specification.

This invention relates to a combined 10 safety razor and hair clipper and it has for an object to provide a simple and inexpensive implement capable of use both in shaving and in cutting the hair.

For further comprehension of the invention, and of the objects and advantages 15 thereof, reference will be had to the following description and accompanying drawings, and to the appended claims in which the various novel features of the invention 20 are more particularly set forth.

Fig. 1 of the drawings is a perspective view of my improved combination implement.

Fig. 2 is a detail end view of the blade 25 carrier and its rotating means.

Fig. 3 is an end view of the implement showing it adjusted for shaving.

Fig. 4 is a similar view showing the implement adjusted for cutting hair.

30 Fig. 5 is a detail plan view of the implement with the handle removed.

Fig. 6 is a detail plan view of the comb unit.

35 Fig. 7 is a detail view part elevation and part axial section, of the handle.

Fig. 8 is a detail perspective view of one of the cutting blades.

In constructing my improved implement I provide a U-shaped yoke or frame 10 to 40 the centre of which a screw 11 is fixed to receive a handle 12. Mounted in the legs of this yoke 10, near the ends thereof, is a shaft 13 having disks 14 fixed to opposite ends thereof, the shaft having diminished 45 ends such as 15 which engage in the yoke legs.

These disks 14 are each formed with a series of slots 17 which are arranged in the sides of a square whose corners lie in the 50 peripheries of the disks, these slots each having one end opening through the peripheries of the disks.

These slots 17 form seats for the ends of 55 resilient blades 18 which extend between the disks 14, the blades having ribs such as 19 extending along their rear edges and en-

gaging in enlargements 20 at the rear ends of the slots 17. To give the blades a shearing action the slots 17 of the respective disks 14 have a staggered relation to one another 60 so that the blades have a spiral inclination.

Suitably journaled in offsets 23 from the yoke 10 is a roller 24, preferably rubber covered, and having a pulley 25 fixed on one end and driving shaft 13 by means of a 65 crossed belt 26, this roller rolling on the face or head when the device is in use.

Carried by the yoke 10 is a comb 28 whose teeth project inwardly under the cutters toward the roller 24, this comb having upwardly and forwardly inclined arms 29 on opposite ends which pivotally engage the ends 15 of the shaft 13. These arms 29 extend rearwardly across the offsets 23 and are adjustably engaged therewith by means 75 of pins such as 30 adapted for insertion in the desired ones of a series of openings 31 with which each offset is provided, these openings lying in the arc of a circle concentric to shaft 13.

The teeth 32 of the comb 28 are curved as seen in face view to cause their inner ends to present diagonal fixed cutter elements 33 co-operating with the blades 18. By adjusting the angle of the comb 28 the height of 85 the fixed cutter elements 33 is varied, to cause the hair to be cut to different lengths. When the device is to be used in shaving the comb is adjusted to the position shown in Fig. 4, permitting the blades to graze the 90 skin.

Having thus described my invention what I claim as new and desire to protect by Letters Patent of the United States is as follows:

1. A device of the class described comprising a series of rotary cutting blades, a yoke supporting said blades, a roller pivoted in offsets from said yoke and positioned in advance of said cutting blades, a drive connection between said roller and cutting blades, a comb having its teeth formed to present diagonal cutting elements co-operating with said blades, a pair of arms on which said comb is carried, said arms being pivoted concentric to said cutter blades, and means for fixing said arms in different positions with respect to the said support. 100

2. A device of the class described comprising a series of rotary cutting blades, a yoke 105 supporting said blades, a roller pivoted in offsets from said yoke and positioned in ad-

vance of said cutting blades, a drive connection between said roller and cutting blades, a comb having its teeth formed to present diagonal cutting elements co-operating with said blades, a pair of arms on which said comb is carried, said arms being pivoted concentric to said cutter blades, and means for fixing said arms in different positions with respect to the said support, comprising a pin carried by one of said arms and adapted to engage in any one of a series of holes in said support.

3. A device of the class described comprising a U-shaped yoke, a handle fixed thereto,

a shaft journaled in said yoke, a pair of 15 disks fixed on said shaft and slotted inwardly at a number of points from the peripheries thereof eccentrically thereto, cutting blades mounted in said slots, a comb having fixed to the ends thereof a pair of 20 arms pivoted on the ends of said shaft, means for adjustably positioning said comb with respect to said yoke, a roller carried by offsets from said yoke, and a drive connection between said roller and said shaft. 25

In testimony whereof I have affixed my signature.

JOSEPH JAKUBIEC.
